LEON FERDINAND BIZOUARNE AND EMILE KUGLER, OF PARIS, FRANCE.

NON-REFILLABLE BOTTLE.

SPECIFICATION forming part of Letters Patent No. 732,506, dated June 30, 1903.

Application filed March 29, 1902. Serial No. 100,547. (No model.)

To all whom it may concern:

Be it known that we, LEON FERDINAND BIZOUARNE, of 34 Rue des Apennins, and EMILE KUGLER, of 28 Rue Fessert, Paris, France, citizens of the Republic of France, have invented new and useful Improvements in Non-Refillable Bottles, of which the following is a full, clear, and exact description.

Our invention relates to improvements in non-refillable bottles, in which we seek to prevent the fraudulent refilling of a bottle or other container with inferior liquor or other substance and at the same time to permit the contents of the container to be readily drawn off, as may be desired.

Further objects and advantages of the invention will appear in the course of the subjoined description, and the novelty will be defined by the annexed claims.

Reference is to be had to the accompanying drawings, forming a part of this specification, in which similar characters of reference indicate corresponding parts in all the figures.

Figure 1 is a vertical sectional elevation of a non-refillable container constructed in accordance with our invention and showing the parts in their normal vertical positions. Fig. 2 is a longitudinal sectional elevation through the container, showing it partly inverted or turned to a pouring position and representing the parts in the positions which they assume on the canting or tilting of the container. Fig. 3 is a detail view of the float-valve removed from the container. Figs. 4 and 5 are views in side elevation of an automatic clamp and counterweight therefor. Fig. 6 is a detail face view of the star-shaped spider.

The container shown by Figs. 1 and 2 of the drawings is represented as a bottle *z*, of any suitable shape, dimensions, and material, said bottle having an annular bead *z'* near its mouth, and this bead is formed with a milled lower edge *f*. Within the neck and mouth of the bottle is arranged a longitudinal cylindrical shell *a*, the same having a contracted portion *b* near its upper end, and this shell is of a length exceeding the bottle-neck in order that the lower part *a'* may extend into the chamber of the bottle or other container. The part *a'* of the shell is constructed with slots or perforations, as shown by Figs. 1 and 2, for the free passage of liquor into or from

the shell during the operation of filling the bottle or decanting the liquid therefrom, and the lower extremity of the slotted part of the shell terminates in a non-perforated foot-piece *a''*, the same having an inwardly-extending ledge or shoulder *v*. The contracted upper part *b* of the internal shell *a* provides an annular space between the neck portion of the bottle and the reduced portion of said shell, which space is adapted to receive a filling-ring of cork or any other suitable material, (indicated at *c*.) thus securing a tight joint between the mouth portion of the container and the mouth portion of the internal shell. Furthermore, the upper contracted part of the shell is formed with a radial flange *a³*, arranged to rest on the top edge of the bottle or other container, and the extreme upper edge of the internal shell is doubled or bent over, as at *e*, in order to rest upon a flanged top edge *d'* of a cap *d*, the lower edge of said cap being doubled, as at *d''*, under the milled lower edge of the collar *z'*. It is to be understood that the filling-ring *c* and the cylindrical shell are slipped into the bottle until the flange *a³* rests on top of the bottle-neck, after which the cap *d* is placed in position for its top edge *d'* to rest on the flange *a³*, while the lower edge *d''* of the cap is turned into engagement with the milled edge of the collar *z'*, and finally the projecting top edge of the cylindrical contracted shell is bent or doubled at *e* into engagement with the cap, thereby securely fixing the cap and the cylindrical shell within the container.

The cylindrical shell *a* is provided with an internal valve-seat *j*, which is located at a point above the slotted or perforated portions *a'* of said shell. Above the valve-seat and within the shell *a* is a buoyant valve *k*, which is made of wood, cork, or any other appropriate material. At its lower portion the buoyant valve is provided with a facing *k'* of any suitable material and fashioned to fit snugly on the valve-seat *j*, while the upper end of this buoyant valve is provided with a star-shaped spider *l*, (see Figs. 1, 3, and 6,) said spider fitting snugly within the casing *a* and serving as a guide to the movement or travel of the buoyant valve.

A collar *i* is secured within the cylindrical casing at a point above the buoyant valve

and below the contracted part *b* of the shell, and this collar is provided with a liquid-passage *i*² and with openings *i*. A conical hood *g* is fixed to the upper part of this collar *i*', so 5 as to partly lie over the liquid-passage *i*² and the openings *i*, said hood being disposed to face toward the passage in and the open end of the contracted portion *b* of the shell. From this hood extends a stem *h*', which passes 10 through the passage *i*² of the collar, and the lower end of this stem carries a mushroom-shaped deflector *h*, the latter lying below the collar and coöperating with the hood *g* in a way to effectually prevent the introduction 15 of a wire or other instrument through the shell in a way to have access to the floatable valve *k*.

From the lower part of the buoyant valve extends a rigid stem *m*, arranged longitudinally and centrally within the slotted part *a'* of the shell, said stem being provided at its lower end with a nut *o* and at a point intermediate of its length with a shoulder *n*. The stem is adapted to be engaged at a point 25 between the shoulder and the nut by the jaws *p* of a clamp which lies within the slotted part *a'* of the shell. This clamp is constructed for its jaws to normally close upon the stem at a point adjacent to the shouldered end thereof, and the upper part of the jaws are provided with inclined faces *p'*, adapted to impinge against the inclined faces *x'* of a collar *x*, which is secured in the slotted part *a'* of the shell at a point below the valve-seat 30 *j*. The inclined faces of this collar *x* are in the path of the similar faces *p'* of the clamp-jaws, and on the movement of the clamp and the collar due to the inversion of the bottle substantially to the position shown by Fig. 35 2 the clamp is pressed against the beveled face of the collar in a way to open the jaws *j* and release them from the stem *m*, thus allowing the stem and the buoyant valve *k* to have a limited slidable movement within the shell *a*, whereby the facing *k'* of this valve is moved away from the seat *j*, so that the liquid will flow freely around the valve and through the collar *i*'.

The clamp is provided on its under side 50 with depending lugs *r*, to which are pivoted the end portions of a yoke *q*, the latter having a depending eye *s*, to which is loosely connected the shank *s'* of a counterweight *t*, said counterweight having an annular rib *u*, 55 which normally lies within the hollow foot portion *a*² of the cylindrical shell. The gravity of the counterweight pulls the yoke and the clamp in a downward direction, so that the jaws of the clamp will engage with the stem, and thus hold the valve *k* to its seat, thus preventing the introduction of any liquid into the bottle.

To pour off the liquid contained in the bottle, it is tilted to the inclined position of Fig. 60 2, thus bringing the rib *u* into engagement with one side of the foot portion *a*², whereby the counterweight *t* is adapted to swing or

turn and to have a slidable movement in the lower part of the casing. This slidable movement of the counterweight pushes the stem *m* downward and forces the clamp *p* in the same direction, so that the beveled faces *p'* of the clamp-jaws are caused to press against the beveled face of the collar, thus spreading the jaws, so as to release the clamp and 70 unseat the valve. With the bottle in the inverted position and the valve *k* unseated any attempt to introduce liquid will lift the float by the pressure of the liquid, thus pushing the valve to its seat and interrupting communication between the chamber of the bottle and the passage in the cylinder *a*. If it is desired to arrest the outflow of the liquid, the bottle-neck should be raised slightly, thus causing the counterweight to swing in one 75 direction and pull the stirrup *q*, which transmits movement to the clamp. This closes the jaws of the clamp on the stem and pulls on the float through said stem, thereby seating the valve *k*. The closing of the valve is 80 effected by turning the bottle at an angle substantially of forty-five degrees, and it will be understood that the valve cannot be opened when the bottle assumes any position between the angles of forty-six and ninety (46 and 90) 85 degrees.

Having thus described our invention, we claim as new and desire to secure by Letters Patent—

1. In a non-refillable bottle, the combination 100 with a valve-seat, of a valve provided with a stem, a clamp fitted to the stem and having jaws arranged to grip the stem, a counterweight connected to the clamp, and means for opening the clamp-jaws and releasing the counterweight from the valve-stem on inversion of the bottle.

2. In a non-refillable bottle, the combination 110 of a casing having a valve-seat, and a stop-shoulder near one end of said casing, a valve having a stem, a clamp fitted in said casing and having beveled jaws arranged to grip the stem, a counterweight connected to the clamp, and a beveled collar lying in the path of the clamp-jaws to engage therewith 115 on inversion of the bottle.

3. In a non-refillable bottle, the combination 120 with a bottle-neck, of a casing secured therein, a collar *i*² within the casing, a hood located above and supported by the collar, a deflector suspended from said collar, a buoyant valve having a spider and fitted slidably in the casing below the deflector, and a counterweight loosely connected to said valve.

4. In a non-refillable bottle, the combination 125 of a casing provided with a valve-seat, a stop-ledge *v* in the casing below the valve-seat, a collar *x* in the casing between the valve-seat and the stop-ledge, a valve, a stem attached to the valve, a clamp fitted to the 130 stem and adapted to engage the collar *x*, and a counterweight suspended from the clamp.

5. In a non-refillable bottle, the combination of a lining or casing adapted to be se-

cured within the bottle-neck and provided with a valve-seat, a deflector within said casting and above the valve-seat, a stop ledge or shoulder *v* also within said casing and below 5 the valve-seat, a valve adapted to said seat, a counterweight adapted to the ledge or shoulder, and loose connection between the valve and the counterweight.

6. A non-refillable bottle having a collar *v* 10 therein, a conical hood spaced with relation to one side of the collar, a deflector spaced relatively to the other side of the collar, said hood and deflector leaving liquid-spaces be-

tween themselves and the collar, and a valve within the bottle-neck and below the deflector. 15

The foregoing specification of our improved means for preventing the fraudulent refilling of bottles and other containers signed by us this 14th day of March, 1902.

LEON FERDINAND BIZOUARNE.
